UNITED STATES PATENT OFFICE.

JOSEPH STARKL, OF CHICAGO, ILLINOIS, ASSIGNOR OF ONE-HALF TO HENRY HEIDELBERGER, OF CHICAGO, ILLINOIS, AND ONE-HALF TO CHARLES C. MADSEN, OF CHICAGO, ILLINOIS.

ENVELOPE OPENER.

Application filed October 11, 1922. Serial No. 593,708.

To all whom it may concern:

Be it known that I, JOSEPH STARKL, a citizen of Austria (who has made application for naturalization as a citizen of the United States), residing at Chicago, in the county of Cook and State of Illinois, have invented certain new and useful Improvements in Envelope Openers, of which the following is a specification.

This invention relates to hand-operated tools for opening envelopes, and has reference more particularly to that type of tool which does its work by cutting a narrow strip from one edge of the closed envelope, or trimming off the fold which integrally joins the front and back sides of the envelope; this being accomplished by a simple relative longitudinal sliding movement of the tool and the envelope.

The main object of the present invention is to provide a simple, inexpensive, and efficient hand tool by which envelopes and similar articles may be expeditiously opened without any danger of cutting or otherwise injuring the contents of the envelope. Other objects are to provide an improved means for effecting the shearing action of the rotary cutter blades under a friction drive of the envelope itself, and to provide an improved means for insuring a clean shear cut of the cutting blades by maintaining thelapping portions of their cutting edges always in close contact.

Other objects and attendant advantages of the invention will be apparent to persons skilled in the art as the same becomes better understood by reference to the following detailed description, taken in connection with the accompanying drawing in which I have illustrated a practical and workable embodiment of the invention, and wherein—

Fig. 1 is a perspective elevation, illustrating the manner of using my improved envelope opener;

Fig. 2 is an inner side elevation of the tool;

Fig. 3 is an edge elevation, viewed from the lower side of Fig. 2;

Fig. 4 is an end elevation viewed from the left of Fig. 2;

Fig. 5 is an enlarged section on the line 5—5 of Fig. 2; and

Fig. 6 is a cross-section through the handle taken on the line 6—6 of Fig. 2.

The frame or body of the tool is conveniently made in a single casting, preferably of aluminum, and comprises generally a head portion 10 and a handle 11. The head 10 is slotted throughout substantially its full length and width, leaving parallel outer and inner walls 12 and 13, between which the cutters and their associated driving and tensioning devices are located. The inner side of the handle 11 is formed with a longitudinal slot 14, the side walls of which are preferably beveled or chamfered, as shown at 15 in Figs. 2 and 6; and the slot 14 is extended through the inner wall 13 of the head, as shown at 14'. Preferably the outer sides of the handle 11 are concave, as shown at 16, creating shallow depressions which afford an improved grip of the thumb and fore finger on the handle, but this feature is, of course, optional. Preferably also the ends of the slotted head 10 are formed with curved guards or covers 17 on the side adjacent to the handle to prevent any danger of cutting the thumb and finger of the user resulting from grasping the handle too closely to the head.

Extending between the front and rear walls of the head are a pair of pins 18, preferably having a taper fit with their receiving apertures in the walls so that they can be driven in with a permanent fit. These pins 18 constitute fixed supports in the nature of shafts, on which the cutter blades, their driving discs and spacing washers are rotatably mounted. Rotatable on each of the pins 18 is a hub member 19; and tightly fitted on these hub members are a pair of friction cutter driving discs 20 preferably of soft rubber or equipped with soft rubber treads. These discs lie in the same plane and are normally in peripheral contact at the center of the slot 14', as clearly shown in Figs. 4 and 5. Between each disc 20 and the adjacent wall 13 is preferably located a thin metal washer 21 designed to reduce the side friction of the rubber disc against the wall of the head.

On the opposite sides of the driving discs 20 are located the two circular steel cutter blades 22 formed with beveled peripheries, as shown in Fig. 5, which overlap at the center of the slot 14' directly opposite the contact point of the peripheries of the discs 20. The sheer relation of the edges

of the blades is obtained by locating one of the blades directly against the driving disc 20, and offsetting the other blade by an interposed friction washer 23. On the left ends 5 of the hubs 19, as shown in Fig. 5, are mounted a pair of metal discs 24 and 25 spaced from the cutter blades 22 by interposed spacing washers 26 and 27, respectively. The peripheries of the discs 24 and 10 25 overlap at a point directly opposite the overlapping portion of the peripheries of the cutter blades; and the disc 25 is of steel or other resilient metal, and constitutes a spring to force its associated cutter disc 22 snugly against the co-operating cutter disc 15 throughout the overlapping area of their cutting edges. It will be observed by reference to Fig. 5 that the spring disc 25 is slightly sprung inwardly between the hub 20 and the point at which it overlaps the periphery of the co-operating disc 24. The spring disc 25 is locked on the hub 19 by spreading the end of the latter over the inner periphery of the disc 25 as indicated 25 in Fig. 5; and it will further be understood that all of the rotary elements assembled on the hubs 19 are tightly fitted on the latter so as to turn therewith, the hubs themselves turning freely on the pivot pins or shafts 18. 30 The manner of using the device is illustrated in Fig. 1, from which it will be seen that the handle of the tool is grasped by the thumb and fore finger of one hand, while the envelope is similarly grasped at its 35 upper end adjacent to the edge to be cut by the thumb and fingers of the other hand, the edge of the envelope is entered into the slot 14 of the handle, being guided by the bottom of said slot, and the tool is then 40 drawn quickly downwardly or inwardly over the edge. This brings the margin of the envelope into the grip of the friction discs 20, imparting rotation to the latter and thus to the rotary cutters 22. The cutting 45 portions of the blade edges sever the strip always at a point opposite to and in the transverse plane of the gripping point of the discs 20 with the front and rear sides of the envelope, so that the latter is squeezed 50 and held rigidly just inwardly of the continuously progressing point at which the cutting takes place. This insures a clean cut in a straight line parallel with the edge of the envelope and so closely adjacent to the latter as to cut off practically only the 55 very narrow web connecting the front and back sides of the envelope, and thus avoiding all danger of cutting the contents of the envelope. The cutting efficiency of the tool 60 is due mainly to two structural features, one of which resides in the means by which the marginal portion of the envelope is tightly gripped always opposite the cutting point, and the other of which resides in the 65 means by which the shear edges of the

cutters are elastically pressed together at their overlapping portions, thereby insuring a clean shear cut.

Manifestly the device comprises relatively few parts capable of being easily assembled 70 in co-operative relation, thus enabling the complete tool to be manufactured at a low cost. I have herein shown and described one physical embodiment of the invention which in practice has been found to satisfactorily fulfill the stated purposes and objects; but it is manifest that the structural details are capable of modification without involving any departure from the operative principle of the invention or sacrificing any of its advantages. Hence, I reserve such variations and modifications as fall within the spirit and purview of the appended claims. 75

I claim—

1. An envelope cutter comprising a hollow head and a handle, said handle formed with a longitudinal slot extending across one side of said head to receive and guide an edge of the envelope, a pair of circular cutters journaled in said head and having their cutting edges overlapping within said slot, and a pair of friction rollers also journaled in said head with their peripheries substantially contiguous within said slot, said rollers serving to grip the margin of the envelope laterally opposite to the overlapping edges of said cutters. 90

2. An envelope cutter comprising a hollow head and a handle, said handle formed with a longitudinal guide slot extending across one side of said head, a pair of circular cutters journaled in said head with their cutting edges overlapping within said slot, and a pair of friction rollers also journaled in said head coaxially with said cutters and with their peripheries substantially contiguous within said slot, said rollers serving to grip the margin of the envelope laterally opposite to the overlapping edges of said cutters and also serving to drive the latter under frictional rolling contact with the envelope. 105

3. An envelope cutter comprising a hollow head and a handle formed with a continuous guide slot extending lengthwise of the handle and across one side of said head, a pair of pivot pins mounted in and crosswise of said head, a pair of cutter discs rotatable on said pivot pins, respectively, with their cutting edges overlapping within said slot, and a pair of rollers rotatable on said pivot pins and drivingly connected to said cutter discs, said rollers being in rolling contact with each other at a point in said slot laterally opposite to the overlapping edges of said cutter discs. 115

4. An envelope cutter comprising a hollow head and a handle formed with a continuous guide slot extending lengthwise of the han- 130

- dle and across one side of said head, a pair of pivot pins mounted in and crosswise of said head, hub members rotatably mounted on said pivot pins, respectively, a pair of cutter discs fixedly mounted on said hub members, respectively, with their cutting edges overlapping within said slot, and a pair of friction rollers fixedly mounted on said hub members laterally opposite to said cutter discs, said rollers being in rolling contact with each other at a point in said slot laterally opposite to the overlapping edges of said cutter discs. 5
5. An envelope cutter comprising a hollow head and a handle formed with a continuous guide slot extending lengthwise of the handle and across one side of said head, a pair of circular cutters journaled in said head with their cutting edges overlapping within said slot, a pair of friction rollers also journaled in said head and drivingly connected to said cutters, said rollers being in rolling contact with each other at a point in said slot laterally opposite to the overlapping edges of said cutters, and spring 20 means for pressing the overlapping portions of said cutters into snug contact with each other. 25
6. An envelope cutter comprising a hollow head and a handle formed with a continuous guide slot extending lengthwise of the handle and across one side of said head, a pair 30
- of pivot pins mounted in and crosswise of said head, hub members rotatably mounted on said pivot pins, respectively, a pair of cutter discs fixedly mounted on said hub members, respectively, with their cutting edges overlapping within said slot, a pair of friction rollers fixedly mounted on said hub members laterally opposite to said cutter discs, said rollers being in rolling contact with each other at a point in said slot laterally opposite to the overlapping edges of said cutter discs, and a spring washer fast on one of said hub members and exerting an endwise thrust on the latter whereby its associated cutter disc is pressed into snug contact with the co-operating cutter disc throughout the overlapping portions of said cutter discs. 35
7. An envelope cutter comprising a hollow head and a handle formed with a continuous guide slot extending lengthwise of the handle and across one side of said head, a pair of cutter discs journaled in said head with their cutting edges overlapping within said slot, and a pair of rubber rollers journaled in said head coaxially with said cutter discs and drivingly connected to the latter, said rollers being in rolling contact with each other at a point in said slot laterally opposite to the overlapping edges of said cutter discs and closely adjacent to the latter. 40
